UNITED STATES PATENT OFFICE

HARRY R. HOLDEMAN, OF LOS ANGELES, CALIFORNIA, ASSIGNOR TO J. M. FELDMAN CO. INC., OF LOS ANGELES, CALIFORNIA

DESIGN FOR A PANEL FOR LIGHTING FIXTURES OR SIMILAR ARTICLES

Application filed June 5, 1929. Serial No. 31,546. Term of patent 7 years.

To all whom it may concern:

Be it known that I, HARRY R. HOLDEMAN, a citizen of the United States, residing at Los Angeles, in the county of Los Angeles and State of California, have invented a new, original, and ornamental Design for Panels for Lighting Fixtures or Similar Articles, of which the following is a specification, reference being had to the accompanying drawing, forming part thereof.

Fig. 1 shows a front view of the panel and Fig. 2 shows a side elevation thereof.

The article shown in the figures is substantially flat and the rear side thereof is devoid of surface ornamentation.

I claim:

The ornamental design for a panel for lighting fixtures or similar articles, as shown and described.

HARRY R. HOLDEMAN.
